[57] **CLAIM**

The ornamental design for a bottle wrap, as shown and described.

DESCRIPTION

FIG. 1 is a left side elevation view of a bottle wrap showing my new design;

FIG. 2 is a top plan view thereof;

FIG. 3 is a right side elevation view thereof;

FIG. 4 is a bottom plan view thereof;

FIG. 5 is a front elevation view thereof; and,

FIG. 6 is a rear elevation view thereof.

The broken line showing of the bottle is for illustrative purposes only and forms no part of the claimed design.
